UNITED STATES PATENT OFFICE.

DAVID L. LAWSON, OF ORBY, CALIFORNIA.

LUBRICATING ATTACHMENT FOR SPRINGS.

Application filed December 9, 1921. Serial No. 521,176.

To all whom it may concern:

Be it known that I, DAVID L. LAWSON, a citizen of the United States, and a resident of Orby, in the county of Santa Barbara and 5 State of California, have invented certain new and useful Improvements in Lubricating Attachments for Springs, of which the following is a specification.

This invention relates to a lubricating attachment for springs.

The invention has for its object to provide a lubricating device as above characterized for supplying a lubricating oil between the leaves of an elliptic or semi-elliptic vehicle 15 spring in a uniform manner, whereby undue pressure and friction between the springs may be obviated.

It is also an important object of the invention that the lubricating attachment be 20 adapted to closely regulate the amount of oil to be supplied to the springs being lubricated and at no time to supply an excessive quantity of oil.

Other objects and objects relating to details of construction, combination and arrangement of parts will hereinafter appear in the detailed description to follow.

The invention is illustrated by way of example in the accompanying drawings, in 30 which:—

Figure 1 is a perspective view of a fragmentary portion of a leaf spring and illustrating the invention applied,

Figure 2 is a vertical sectional view of the 35 same taken adjacent one side of the leaf spring,

Figure 3 is a transverse sectional view of the same,

Figure 4 is a detail sectional view showing a partial inner face of one of the wick 40 or pad holders and a portion of the supplemental oil tube.

Referring to the drawings more particularly, 10 indicates generally a casing which 45 is U-shaped and its bridge portion 11 occurring a distance above the lower ends of its leg portions 12. The leg portions 12 of the U-shaped casing, in each instance, are open at their inner sides and each adapted to receive a wick or pad 13, said pads being preferably of felt, and each pad extending through a suitable recess formed in the bridge portion 11 of the casing and having its lower end disposed below the bridge portion 11 as shown in Figure 3.

The legs 12 are spaced sufficiently that

they may be fitted upon a plurality of superposed leaf springs 15, as shown. The upper end of each leg portion 12 of the casing terminates in an upstanding flange 16 which is 60 arcuate in shape, as shown, and said flanges are provided with suitable openings through which a bolt 17 may be extended, said bolt carrying the nut 18 by which the same is secured against removal and the casing 65 secured to the spring leaves.

For telescoping the lower portion of casing 10 there is provided a cap 18' which is adapted to serve as a bottom to close the space between the lower ends of the legs 12 70 and thus form a receptacle in which a suitable lubricant may be retained as indicated at 19. The cap 18' is formed with a lip 20 about its upper edge which is adapted to be engaged by the spring fingers 21 for remov- 75 ably holding the cap in its applied position.

Each spring finger is provided with an extension 21' to facilitate the lifting of the same. Also the lips 20 serve to catch any excess oil which may travel down the outer 80 sides of the legs 12. The oil caught by the lips 20 would of course find its way to the body of oil 19.

In one leg 12 of the casing there is positioned a tube 22 which extends near the bottom of the leg and its upper end communicates with an oil opening 22' formed in the leg. The oil opening may have a cover 23 which will tightly close the same to prevent dust or other foreign matter entering the 90 same.

In attaching the lubricating device heretofore described, the cap 18' is first filled with oil and the wicks 13 are positioned, and the device secured to a spring by the means 95 of the bolt 18, as shown. In operation the oil from the cap 18' is fed by a capillary attraction to the leaves of the spring and allowed to enter therebetween. By this arrangement of emitting the oil to the spring 100 leaves, a close regulation of the amount of oil distributed is had, and as obvious the quantity of oil fed will be uniform and at no times excessive. Should it some time be desired to saturate the wicks then oil may be 105 injected through the oil opening 22'. This of course is only necessary when an excessive amount of oil is desired for lubricating the spring means. Ordinarily the oil contained in the cap 18' of the casing 10 will be sufficient. As is obvious the cap 18 is of sufficient size to hold oil for lubricating the 110

spring leaves for a long period without replenishing, and when replenishing the same may be easily and quickly accomplished.

I claim:

- 5 1. A leaf spring lubricating attachment, comprising a U-shaped member adapted to be fitted upon a leaf spring construction, the leg portions thereof being channeled shaped on inner side and extending below the bridge portion, a wick within each leg portion and extending through an opening in the bridge portion so that the lower ends of said wick may depend below the bridge portion, and a removable lubricating pan fitted upon the 10 extended portions of said legs.
2. A leaf spring lubricating attachment, comprising a U-shaped member adapted to be fitted upon a leaf spring construction, the leg portions thereof being channeled shaped 15 on inner side and extending below the bridge portion, a wick within each leg portion and extending through an opening in the bridge portion so that the lower ends of said wick may depend below the bridge portion, a pan receptacle telescoping the 20 extended portions of said legs and detachable connecting means between said pan and said legs.

3. A leaf spring lubricating attachment, comprising a U-shaped member adapted to be fitted upon a leaf spring construction, 30 the leg portions thereof being channeled shaped on inner side and extending below the bridge portion, a wick within each leg portion and extending through an opening 35 in the bridge portion so that the lower ends of said wick may depend below the bridge portion, a pan telescoping said legs, having an outwardly curved lip formed about its upper edge and adapted to retain a lubricating liquid, and means for detachably securing said pan to the legs.

4. A leaf spring lubricating attachment, comprising a U-shaped member adapted to be fitted upon a leaf spring construction, the 45 leg portions thereof being channeled shaped on inner side and extending below the bridge portion, a wick within each leg portion so that the lower ends of said wick may depend below the bridge portion, a pan telescoping 50 the extended portions of said legs and having an outwardly curved lip formed about its upper edge, a spring finger carried by each lip and adapted to engage each lip whereby to detachably hold said pan.

DAVID L. LAWSON.
